UNITED STATES PATENT OFFICE.

LEO DAFT, OF PLAINFIELD, NEW JERSEY.

ARMATURE FOR DYNAMO-ELECTRIC MACHINES.

SPECIFICATION forming part of Letters Patent No. 396,195, dated January 15, 1889.

Application filed November 12, 1885. Renewed May 4, 1888. Serial No. 272,855. (No model.)

To all whom it may concern:

Be it known that I, LEO DAFT, a subject of the Queen of Great Britain, and a resident of Plainfield, in the county of Union and State 5 of New Jersey, have invented certain new and useful Improvements in Armatures, of which the following is a specification.

My invention relates to dynamo or magneto electric generators or motors; and it has for 10 its object to improve the mechanical construction of the armature-cores of such machines, so as to render them strong and firm, and to furnish them with means for the rigid attachment of the spider-arms that support the core 15 and to hold it in proper position while under heavy strain, and at the same time permit the ready removal of the armature-shaft without disturbing the electrical connections.

To these ends my present invention consists 20 of an armature-core constructed substantially as more particularly pointed out hereinafter.

Referring to the accompanying drawings, Figure 1 is an end view of a core, showing 25 the outer ring and spider-arms. Fig. 2 is a side view, partially in section. Fig. 3 is a similar view showing a modified core or cylinder.

Great difficulty has been heretofore experienced 30 in properly supporting the core of armatures in machines used for heavy work, such as on electric locomotives and the like, where the machine has to be started and stopped frequently and is under great strain. Numerous attempts have been made to overcome 35 these mechanical objections, and they have usually resulted in the use of large masses of magnetic material in and around the core and windings, which is very objectionable, as the said material tends to weaken 40 the effect of such machines by the formation of the so-called "Foucault" currents, which not only waste the magnetic effect of the machines, but cause heating of the parts, which 45 interferes with the proper operations of the machines.

It is usual to form the core or cylinder of some material, or in some arrangement of parts, so that the evils of these currents are 50 overcome; and in the accompanying drawings I have shown the body of the core H in Fig. 2 as made up of soft-iron wire and supported

between the rings C, and in Fig. 3 the body H of the core is made up of soft-iron rings or washers alternating with similar forms of insulating material and having the rings C at the ends. These rings C, I form of some diamagnetic material—such as phosphor-bronze—and these furnish an outer peripheral surface of the core, which may be readily 55 turned true to afford a suitable foundation for the coils of wire forming the armature.

It has been customary to support the core or cylinder upon spider-arms attached directly to the peripheral rings C in various 60 ways; but I have found that a much stronger and satisfactory means of supporting the core in the construction shown in the drawings, and which I am about to describe.

Between the core H and the ring C, I interpose a ring, A, composed of phosphor-bronze or other suitable material, preferably of a diameter to correspond to the periphery of the armature when the wires are applied, and cast or formed integral with this ring 70 are the arms B B, projecting laterally therefrom. These arms fit in slots or recesses formed or milled into the outer edge of the ring C, and extend outward to the spider-ring D, which is mortised or recessed to receive 75 the ends of the arms and to insure the proper centering of the armature-shaft upon which the spiders are secured. These arms are secured in place in the recesses by any suitable and well-known means.

From this construction it will be obvious 80 that there is a strong and rigid connection between the spiders and the core without the use of any screws or bolts that will be liable to work loose and destroy or injure the armature by grinding between the periphery of the armature and the interior of the field-magnets, and that the parts of the armature will be held in place and still may be readily removed from its shaft without liability of 85 disturbing the insulation of the windings thereon.

I claim—

1. An armature consisting of a cylindrical core, rings connected to the core and having 90 outwardly-extending arms, and spiders connected to said arms, substantially as described.

2. The combination, with the core, of a

ring, another intermediate ring interposed between the core and the said ring, a spider, and arms joining the spider and intermediate ring, substantially as described.

- 5 3. The combination, with the core, of a ring having notches, an intermediate ring having laterally-projecting arms fitting said notches, and spider-arms supporting the latter, substantially as described.
- 10 4. In an armature, the combination, with the core, of a ring of diamagnetic material, over which the wires may be wound, an in-

termediate ring having integral arms, also of diamagnetic material, and spider-arms connected to the intermediate ring supporting 15 the core, substantially as described.

In testimony whereof I have signed my name to this specification in the presence of two subscribing witnesses.

LEO DAFT.
